(57) **CLAIM**

The ornamental design for a electronic battery tester, as shown and described.

DESCRIPTION

FIG. 1 is a front perspective view of the electronic battery tester.

FIG. 2 is a right side plan view of the electronic battery tester.

FIG. 3 is a left side plan view of the electronic battery tester.

FIG. 4 is a top plan view of the electronic battery tester.

FIG. 5 is a bottom plan view of the electronic battery tester.

FIG. 6 is an upper end plan view of the electronic battery tester; and,

FIG. 7 is a lower end plan view of the electronic battery tester.
